FRACTURE REDUCING APPARATUS

Victor Carabba, New York, N. Y.

Application November 13, 1935, Serial No. 49,491

6 Claims. (Cl. 128—84)

The present invention relates to fracture reducing apparatuses and relates more specifically to an apparatus for the treatment of fractures of the os calcis.

5 The occurrence of the more serious fractures of the os calcis is relatively small compared to the fractures of other bones. The percentage of these fractures requiring radical surgical intervention, compared with fractures of the long 10 bones, is also small. When however, the surgeon is confronted with a badly displaced simple or comminuted fracture of the os calcis, he is faced with a serious problem. Orthopedic surgeons frequently advise immediate arthrodesis, 15 while others maintain the more conservative position of employing surgical means for effecting the reduction.

20 The principal object of the present invention is to provide a simple and inexpensive apparatus for the reducing of fractures of the os calcis which is particularly efficacious in cases of badly comminuted and displaced fractures.

25 Another object of the invention is the provision of a device for the reduction of fractures of the os calcis which will reduce the pain and inconvenience of the patient to a minimum.

30 The use of the Steinman pin in the reduction of bone fractures is well known. This pin is split in the center and is provided with screw-threaded male and female meeting portions, the central portion of the pin being of larger diameter than the end portions thereof, which latter are tapered. The pin is driven through the fractured bone by the use of a hammer and 35 after the reduction has been made, the pin is suitably secured at the ends thereof to maintain the reduction until the fractured portions have united. Up to the present time, however, no suitable apparatus has been devised which 40 effectively permits the use of the pin in the reduction of fractures of the os calcis.

45 The present invention includes a frame which is secured at its opposite ends to a plaster cast boot which has been previously applied to the leg and foot, the heel portion of the foot not being covered with the plaster. A stirrup-like structure is pivotally carried on the frame and is capable of two adjustments to effect posterior and anterior reduction of the fracture. The 50 first adjustment is the pivotal one, whereby the Steinman pin, which is secured to the ends of the stirrup, may be drawn forward to effect posterior reduction. The second adjustment is accomplished by providing means for lengthening 55 and shortening the stirrup to effect anterior re-

duction. Inasmuch as the frame is secured to the plaster rigid boot only, the reduction may be effectively performed without undue pressure on the bones or tissues.

In the drawings, Fig. 1 is a perspective view of 5 the apparatus secured to a plaster cast boot which has been formed upon a patient's foot;

Fig. 2 is a side elevation of the device; and Fig. 3 is a front elevation thereof in perspective.

10 The preferred embodiment of the invention includes a universal fitting central base bar 10, made from a flat strip of metal, the bar having a curved portion 11 at its lower end which fits into the concavity formed by a plaster boot 12 which has been applied to the foot and leg. 15

20 The terminals of the base bar are provided with transversely disposed curved plates 13 and 14 to which straps 15 and 16 are secured, the strap 15 engaging the portion of the plaster cast on the foot, and the strap 16 engaging the calf portion of the leg. A substantially U-shaped brace 18 is secured to the lower end of the base bar by means of screws 19, the brace and the base 25 bar constituting the frame of the device.

25 The adjustable stirrup structure includes a pair of opposed, spaced-apart supporting members 21 having outwardly extending offset portions 22, the member being pivotally carried on a block 23, which is secured to the upper surface of the curved portion 11 of the base bar by 30 means of screws 24, the pivotal element being designated as 25. A pair of L-shaped extensible members or stirrup arms 27 are carried on the offset portions 22 of the supporting member 21 in the following manner. The arms 27 are formed 35 with longitudinal slots 29 through which a pair of spaced screws 30 pass into the lower ends of the offset portions 22. Thus, the extensible members may be moved longitudinally the full length of the slots 29. A pair of opposed angle brackets 40 40 are secured to the upper portions of the supporting members 21 by means of screws 34. A traction screw 35 having a thumb turn 36 is carried at the outer end of each of these angle brackets, the lower end of said screw passing 45 through a threaded aperture 37 in the horizontal portion of the extensible member. Thus, as the thumb turn is rotated, each stirrup arm is caused to move independently upwardly or downwardly, 50 as desired.

55 In actual practice, the arms of the stirrup are so constructed as to be possible of elongation of a distance of five centimeters or thereabouts. The lower ends of the stirrup arms are provided with 55

extension members 39 which carry opposed clamping members 41, which are adapted to firmly support the Steinman pin (not shown) by tightening the thumb turn 42.

5 Rotation of the stirrup structure is accomplished in the following manner. A bracket 44 is secured to the U-shaped brace 18 by means of the screw 19. A traction screw 45, having a thumb turn 46, is carried on the outer end of 10 this bracket, the forward end of the traction screw passing through a block 47, which is pivotally carried between the upper terminals of the supporting members 21 by means of screws 49. As this thumb turn is rotated, the stirrup structure is movable through an arc of approximately 30°.

The operation of the device is as follows: The patient is first given a spinal anaesthesia and, under sterile precautions, a Steinman pin approximately six inches in length is passed 20 through the os calcis at a point one or two centimeters below the attachment of the tendo-achilles. A sterile dressing is now applied to the points of entrance and exit and the Steinman pin 25 and the operative wound through which the tenotomy has been performed. A plaster boot 12 is next applied to the foot and the lower portion of the leg with the foot at right angles and internal rotation, the heel portion of the foot not 30 being covered by the cast. In Fig. 1 the heel portion is shown with a gauze dressing 48.

This fixation of the foot allows any traction applied to the os calcis to act on that bone without movement of any other portion of the foot 35 or ankle. When the plaster boot is thoroughly hardened and dried, the apparatus is strapped onto the foot and leg, as shown in Fig. 1. In most instances, the stirrup arms are fully lengthened and are revolved backwardly to the position 40 shown in broken lines in Fig. 2, prior to the application of the device to the plaster boot, the device then being secured in such a position as to cause the clamping members 41 to be adjacent to the terminals of the Steinman pin when the 45 stirrup is so lengthened and revolved, since the reduction of the fracture normally requires a considerable shortening of the stirrup and a revolution thereof to the position shown in full lines in Fig. 2. The terminals of the Steinman 50 pin are now secured between the portions of the clamping members and a cork 50 placed at each end of the pin to prevent the same from injuring the patient's other foot, and also the tearing of bed linen.

55 The screws 35 are now operated to lengthen the stirrup arms backward. This lengthening is continued until all impaction is broken up and the widening of the body of the os calcis is properly reduced to normal. The screw 45 is next 60 operated to rotate the stirrup arms forward, which rotates the bone fragments downward and forward. This movement represents the exact opposite force which caused the fracture in the first instance. In the event tilting of fragments 65 has occurred to one side or the other, simple over-lengthening of one of the stirrup arms will tilt the pin to correct the tilting fragments. An X-ray is immediately taken and further adjustments 70 made until the fragments are in perfect alinement.

After the reduction has been completed, the apparatus may be removed and the plaster boot completed to incorporate the Steinman pin in the 75 exact position of reduction by the apparatus, the

plaster surrounding the pin and holding the proper alinement of the fragments.

What I claim is:—

1. A device of the class described including, in combination, a base member, means carried 5 adjacent to opposite ends of the base member for securing said base member to the foot and leg of a patient, a shiftable bifurcated element pivotally carried on the base member, traction means for shifting the bifurcated element and for revolving 10 same through an arc, and means adjacent to the terminals of the bifurcated element for receiving an elongated pin.

2. In a fracture reducing apparatus, the combination of a frame, fastening means disposed at 15 opposite ends of the frame for securing the same to the foot and leg of a patient, a stirrup structure pivotally carried on the frame, a pair of independently movable, shiftable arms carried by the stirrup structure, clamping means positioned 20 at the outer terminals of said arms, screw means for shifting said arms and screw means for moving the stirrup structure through an arc.

3. An apparatus for reducing fractures of the os calcis including, in combination, an elongated 25 base member having a curved forward portion adapted to engage the foot of a patient, strap means disposed adjacent to opposite ends of the frame for securing same to the foot and leg of the patient, a shiftable bifurcated clamping element pivotally carried on the base member, and traction means for independently shifting the terminals of the clamping element and traction means for revolving said terminals through an 30 arc.

4. In an apparatus for reducing fractures of the os calcis, the combination of a frame having a curved portion adapted to fit the ankle portion of the patient, means for securing the frame to the leg, a stirrup structure pivotally carried on 40 the frame, a pair of extensible arms carried by the stirrup structure, clamping means positioned at the outer terminals of said arms for securing the terminals of an elongated pin, screw means for lengthening and shortening said arms and 45 screw means for revolving the stirrup structure through an arc.

5. In an apparatus for reducing fractures of the os calcis, the combination of an elongated base member shaped to fit the front leg and ankle 50 portion of a plaster cast which has been formed on the patient's leg and foot, an extensible bifurcated member pivotally carried on the base member, clamping means at the lower end of the bifurcated member for securing the terminals of 55 a Steinman pin or the like, thumb turn actuated screw means for shortening and lengthening the bifurcated member and similar means for revolving the member through an arc.

6. In an apparatus for reducing fractures of 60 the os calcis, the combination of a frame having a curved portion adapted to fit the ankle portion of the patient, means for securing the frame to a plaster boot which has been formed on the leg of the patient, a stirrup structure pivotally carried on the frame, a pair of extensible arms carried by the stirrup structure, clamping means positioned at the outer terminals of said arms for securing the terminals of an elongated pin 65 adapted to be passed through the os calcis, screw means for lengthening and shortening the extensible arms independently of each other, and screw means for revolving the stirrup structure through an arc.
